CONVEYER

William H. Reimann, Hialeah, Fla.

Application April 9, 1941, Serial No. 387,737

1 Claim. (Cl. 198—174)

This invention relates to an improved conveyer and more particularly to a conveyer particularly adapted for use in conveying concrete, mortar and plaster and other fluent mixtures in a manner so that the conveyed mixture will be constantly agitated while in transit to continue the mixing thereof and to effectively prevent the heavier or solid ingredients of the mixture from settling and separating from the lighter or liquid ingredients.

Still another aim of the invention is to provide a conveyer which is likewise adapted for use in conveying brick, coal, crushed stone, sand, gravel, clay, grain and other similar solid or loose materials.

It is the primary object of the invention to provide an improved form of conveyer wherein the conveyer elements or blades are moved through a conveying trough for pushing and/or pulling the material disposed in the trough and which is to be conveyed so that the material will be constantly agitated while in transit and so that regardless of the length of the conveyer the mixture will be as thoroughly mixed upon reaching the outlet end of the conveyer as when admitted thereto.

Another important object of the invention is to provide an improved endless conveyer for concrete, mortar and plaster and similar materials, of the type previously described, and employing endless, flexible power transmitting means so arranged that there is no possibility of any part of the conveyed mixture coming in contact with the flexible power transmitting means which, obviously, would destroy the flexibility and consequently the utility thereof.

Still another aim of the invention is to provide a self-supporting portable conveyer which is adapted to be balanced on a wheeled supporting truck having means for raising and lowering one end of the conveyer and for transporting the conveyer in directions either longitudinally or transversely of the longitudinal axis of the conveyer.

Still another object of the invention is to provide an improved conveyer employing endless flexible conveyer means which are trained over sprockets or pulleys at the ends of the conveyer and which are driven at a plurality of points intermediate of the ends of the conveyer and in opposite directions to thereby prevent slack in the endless conveyer and to insure that all portions of the conveyer will be driven at all times at a uniform speed.

Other objects and advantages of the invention

will hereinafter become more fully apparent from the following description of the drawings, which illustrate preferred embodiments thereof, and wherein—

5 Figure 1 is a side elevational view showing the improved conveyer in its entirety,

Figure 2 is a top plan view of the same,

Figure 3 is an enlarged fragmentary longitudinal sectional view taken substantially along the plane of the line 3—3 of Figure 2,

10 Figures 4, 5 and 6 are enlarged sectional views taken substantially along the planes of the lines 4—4, 5—5, and 6—6, respectively, of Figure 1,

Figure 7 is a transverse sectional view taken substantially along the plane of the line 7—7 of Figure 6,

15 Figure 8 is an enlarged fragmentary longitudinal vertical sectional view, partly in elevation, of the lower, pivotally mounted end of the conveyer,

Figure 9 is an end view partly in section and partly in elevation of the same,

Fig. 10 is a longitudinal horizontal sectional view taken substantially along the plane of the line 10—10 of Figure 8,

Figure 11 is a fragmentary top plan view of a portion of the endless chain conveyer,

Figure 12 is a view similar to Figure 8 of a slightly modified form of the invention,

30 Figure 13 is a view similar to Figure 9 of the modified form, and

Figure 14 is a longitudinal horizontal sectional view taken substantially along the plane of the line 14—14 of Figure 12.

35 Referring more particularly to the drawings, wherein like reference characters designate like or corresponding parts throughout the different views, 15 designates generally the conveyer in its entirety and which includes a supporting 40 wheeled truck, designated generally 16 and a supporting frame, designated generally 17.

The wheeled truck 16, as best seen in Figures 1, 2, 6 and 7 includes side rails, designated generally 18, each of which, as best seen in Figures 45 6 and 7, is formed by an H-beam 19, the web 20 of which is disposed in an upright position, and a pair of beams 21, each of which is channel shaped in cross section and which are mounted in the H-beam 19, one on either side of the web 50 20 thereof and which are disposed to open outwardly, as seen in Figure 7. As seen in Figure 6, the channel beams 21 are provided with longitudinally disposed registering slots or elongated openings 22 for receiving the shank of the bolt 55 of a nut and bolt fastening 23 which extends

through an opening 24 in the web 20 for clamping the channel beams 21 to the H-beam 19. It will thus be seen that the side rails 18 are extensible. The side rails 18 are provided with laterally disposed inwardly projecting stub axles 25 on the under side of each end thereof on which are journaled the supporting wheels 26 which are held in position thereon by cotter pins or other suitable fastenings 27. The truck 16 is also provided with stub axles 28 which project from the ends of the rails 18 and to which the wheels 26 may be readily applied by jacking up the truck 16, for a purpose which will hereinafter be described. The stub shafts 28 and the stub shafts 25 are each provided with openings 29 adjacent their outer ends for receiving the cotter pins 27. The truck 16 is provided with a floor 30 which is attached to the upper sides of the fixedly disposed H-beams 19 of the side rails 18. Mounted on the floor 30 of the truck 16 is a motor 31 having a driven shaft 32 on which is keyed a sprocket wheel 33. A jack shaft 34 is journaled in bearings 35 mounted on the floor 30 and is provided with a sprocket wheel 36 which is connected to the sprocket 33 by a chain 31. A second pair of bearings 38 is disposed on the opposite side of the motor 31 to the bearings 35 and connected to the flooring 30 for supporting hoist means, designated generally 39 and which is connected to the shaft 32 by suitable driving means 40.

A shaft 41 is journaled at its ends in bearings 42 at the end of the truck 16, which is remote to its extensible end. The truck 16 is provided with a derrick structure, designated generally 43, including a pair of upright standards 44 which are pivotally connected at their lower ends to the truck 16 by engagement with the shaft 41 and a second pair of diagonally disposed standards 45 which are connected at 46 at their upper ends to the upper ends of the standards 44 by means of a shaft extending through the upper ends thereof. The lower ends of the standards 45 are pivotally connected to brackets 47 which are mounted at the opposite end of the flooring 30.

The frame structure 17 is pivotally connected adjacent one end thereof to the shaft 41. A flexible hoist element 48 is fastened at one end to the upper end of the frame 43 and extends therefrom around an idler pulley 49 which is journaled on the frame structure 17, adjacent its opposite, free end, after which the flexible element 48 extends back over an idler pulley 50 on the shaft 46 and then down and under idler pulleys 51 on the truck 16. The opposite end of the flexible element 48 is wound on a reel 52 forming a part of the hoisting means 39 and which is adapted to be actuated for raising and lowering the outer free end of the conveyer frame structure 17 by the motor 31.

The conveyer frame structure 17 includes spaced sides, designated generally 53 each of which includes an upper and lower inwardly extending channel beam 54, which channel beams extend longitudinally thereof. The sides 53 also include the upright members 55, to which the channel beams 54 are connected and which are braced by the diagonal braces 56. The uprights 55 extend above the upper channel beams 54 and are connected at their upper ends by the upper rails 57 which extend longitudinally of the frame structure 17. The sides 53 are spaced apart, in substantially parallel relationship, by means of the diagonally disposed transverse braces 58 which are connected at their ends to the uprights 55. To the under sides of the lower channel

beams 54 are attached plates 59 which extend inwardly beyond the channel beams 54 and which are provided with upset flanges 60 at their inner ends, for a purpose which will hereinafter become apparent. A conveyer trough 61 is provided with outwardly extending flanges 62 at its rim which are disposed beneath and suitably fastened to the under sides of the plates 59 for mounting the trough 61 beneath the frame structure 17 and centrally thereof. As best seen in Figure 1, the trough 61 extends substantially from end to end of the frame structure 17 and connects at its upper end with a funnel shaped outlet 63 which is attached to the under side of the outer, free end of the frame structure 17 and which is provided with depending telescoping sections 64, as best seen in Figure 1.

The frame structure 17 is provided with a pair of bearings 65 mounted in the upper ends of the sides 53 for journaling a shaft 66 on which is mounted a pair of idler sprocket wheels 67 which are keyed to the shaft 66. The posts 55 at the opposite, lower end of the frame structure 17 are provided with elongated threaded bolts 68 which project outwardly therefrom longitudinally of the frame 17 and on which is slidably mounted a plate 69 which is adapted to be moved toward and away from the frame 17 and retained in adjusted positions by means of follower nuts 70 which are in threaded engagement with the bolts 68 and which are arranged in pairs on opposite sides of the plate 69. The plate 69 is provided at its ends with outwardly projecting bearing members 71 the outer ends of which journal a shaft 72 to which is keyed a pair of sprocket wheels 73 which are arranged to align with the sprocket wheels 67 and which are of substantially the same diameter.

A pair of endless chains 74 are trained over the complementary sprocket wheels 67 and 73. The chains 74 are provided with flanged rollers 75 which are journaled on the pins 76 which connect the links forming the chains 74. The chains 74, as best illustrated in Figures 4 and 5, extend through the channel beams 54 with the tread of the rollers 75 engaging the lower sides thereof. The flanges of the rollers passing through the lower channel beams 54 extend into the spaces 77 between the outer edges of the lower sides of the channel beams 54 and the flanges 60.

Referring particularly to Figures 1, 2 and 3, the sides 53 intermediate of their ends are provided with three spaced upright members 78. In the remotely disposed pairs of the uprights 78 are journaled the transversely disposed shafts 79 to which are keyed the sprocket wheels 80 which are disposed between said uprights 78 and also between the upper and lower channel beams 54 which, as seen in Figure 3, are provided with cut-out portions 81 in their adjacent sides through which portions of the sprocket wheels 80 extend and so that the teeth thereof engage the chains 74. The chains 74 extend downwardly and outwardly through the cut-out portions 81 of the upper channel beams 54 and are trained under idler sprocket wheels 82 which are keyed to stub shafts 83 which are journaled in and extend inwardly from the intermediate uprights 78. The sprocket wheels 82 extend into the upper channel beams 54 through cut-out portions 82'. The adjacent ends of the stub shafts 79 are spaced substantially apart, for a purpose which will hereinafter become apparent.

Referring particularly to Figures 1 and 2, shafts 37 and 41 are provided with sprocket wheels, not

shown, over which are trained chains 84 for driving the shaft 41 off of the jack shaft 34. A shaft 85 is journaled in an opposed pair of the uprights 55, adjacent the lower end of the frame 17. A pair of sprocket wheels, not shown, is keyed to each end of the shaft 85. A pair of chains 86 are trained over the inner sprocket wheels of each of the pairs of sprocket wheels keyed to the shaft 85 and over a pair of sprocket wheels, not shown, keyed to the shaft 41. The next pair of uprights 55, toward the upper free end of the frame 17, likewise journal a shaft 87 which is provided with a pair of sprocket wheels, as shown, at each end. The outer sprocket wheels of shafts 85 and 87 are connected by chains 88. The next pair of uprights 55, toward the free end of frame 17 journal a shaft 89 also provided at each end with a pair of sprocket wheels. The inner sprocket wheels of shafts 87 and 89 are connected by chains 90. The shaft 79, adjacent shaft 89 is provided with a pair of sprocket wheels 91 at each end, as seen in Figure 5. Outer sprocket wheels 91 are connected to the outer sprocket wheels of shaft 89 by chains 92. The other shaft 79 is provided with one sprocket wheel at each end, as shown, which are connected by chains 93 to the inner sprocket wheels 91. It will thus be seen that through the chain, sprocket wheel and shaft connection just described that the sprocket wheels 80 are driven at uniform speeds and in a counterclockwise direction, as seen in Figure 3, by motor 31 so that the lower portion of the chains 74 will move toward the upper, outer end of the frame structure 17.

Chains 74, as best seen in Figure 11, are provided with connecting cross bars 94 having angular ends 95 connected by fastenings 96 to the inner sides of alternate links of chains 74. A supporting arm 97 is attached to and projects outwardly from each bar 94. A yieldable conveyer element or blade 98 is fastened to and projects outwardly from each arm 97. Arms 97 are connected to bars 94 and blades 98 by fastenings 99 (Figure 4). The blades 98 are provided with rounded free ends and are sized to fit snugly crosswise of the lower part of the trough 61 (Figure 4). Blades 98 terminate substantially below the rim of trough 61, for a purpose which will hereinafter be described.

Bars 94 have pairs of plates 100 adjacent each end and transversely thereof forming shields. Frame 17 has aprons or shields 101 fastened to its uprights 55 and extending from end to end thereof. Aprons 101 extend inwardly and downwardly of frame 17 and open between the pairs of plates 100 and above trough 61. The trough 61 is provided at its rim with the flanges 102 which extend upwardly and outwardly therefrom and which terminate beneath the bars 94 and on the outer sides of the pairs of plates 100. The shields 103 are attached to the upper portions of the upper channel beams 54 and extend upwardly and inwardly over the upper portions of the chains 74 and are provided with downwardly and inwardly extending free ends which terminate adjacent the outer sides of the pairs of plates 100.

The supporting arms 97 are provided with eyelets 104 on their rear sides and the blades 98 are provided with eyelets 105 on their forward sides and adjacent their outer, free ends. The eyelets 104 and 105 are connected by flexible drag means such as the chains 106 in a manner so that each of the blades 98 is connected to the next preced-

ing supporting arm 97, as best seen in Figures 3 and 8.

As best seen in Figure 8, a trough section 107, which is slightly larger than the trough 61 has an end telescoping over the lower end of the trough 61 and forming a continuation thereof. The opposite end 108 of the trough section 107 is curved upwardly and disposed concentric to the sprocket wheels 73. A hood or cover 109 is disposed over the sprocket wheels 73 and engages over a portion of the trough section 107. The hood 109 is provided with outwardly projecting apertured ears 110 having apertures arranged to register with apertures in corresponding ears 111 of the plate 69 and which are connected by fastenings 112 for detachably mounting the hood 109 in position, as illustrated in Figure 8.

The opening 113 in the frame structure 17, adjacent its lower end forms a hopper through which the material to be conveyed upwardly through the trough 61 is discharged into the trough.

The conveyer 15, illustrated in Figures 1 to 11, inclusive, may be made in various sizes with the frame structure 17 of various lengths up to approximately sixty feet and with the trough 61 of various widths. The drag chains 106 are provided only if the conveyer 15 is of a relatively small size to prevent the chains 74 from kinking and buckling and to prevent the blades 98 from bending back under the load being conveyed through the trough 61 and thereby permitting parts of the load to be released. On larger sized machines 15 where heavy chains which will not kink or buckle are used and where the blades 98, which are preferably formed of rubber, are thicker and of a heavier construction the drag chains 106 may be omitted because the blades 98 are sufficiently rigid to withstand the pressure of a normal load conveyed thereby.

The conveyer 15 is adapted to be towed on its ground wheels 26 to the location where it is to be used after which the truck 16 is preferably jacked up and the wheels 26 removed from the axles 25 and applied to the axles 28 so that the truck 16 may be moved laterally to better accommodate it to be positioned so that its outlet 63 will be over the point where the material conveyed by the machine 15 is desired to be discharged. The hoist means 39 is then operated by the motor 31 to raise the outer, free end of the frame structure 17 to the desired elevation. The hoist means 39 includes suitable clutch means, not shown, for disengaging it from the motor 31 and suitable means for applying a brake thereto to retain the frame structure 17 in an inclined position. The motor 31 is then employed to cause the endless chains 74 and the conveyer blades 98, carried thereby, to be moved in the direction, previously described, and indicated by the arrow, designated 114, in Figure 1. The chains 74 are driven by the chain, sprocket wheel and shaft driving means previously described, which drive the sprocket wheels 80 and one of the particular advantages of the invention resides in the fact that instead of driving the chains 74 from one of the ends of the frame structure 17, as is the conventional manner, the chains 74 are driven at two spaced points intermediate of their ends and in opposite directions so that both the upper and the lower portions of the chains 74 will be driven simultaneously at uniform speeds to prevent the chains 74 from sagging or dragging. The chains 74, as seen in Figure 3, are trained under the idler sprocket

wheels 82 for not only tensioning them but for insuring that the chains engage the teeth of the sprocket wheels 80 in the return movement of the conveyer elements 98 towards the lower end of the frame structure 17. The stub shafts 83 are spaced to permit the blade elements 98 and their supporting arms 97 to pass therebetween. Obviously, the idler sprocket wheels 73 may be adjusted relatively to the frame structure 17 by means of the bolts 68 and nuts 70, as previously described, for tensioning the chains 74. The diameters of the sprocket wheels 73 are such that the chains 74 can pass thereover without the blades 98 being bent excessively by the drag members 106, as illustrated in Figure 8. The blades 98 passing around the sprocket wheels 73 will move into the open end of the upturned portion 108 of the extensible section 107 from where they will move into the lower end of the trough 61 where each blade 98 in turn will pick up a load of the material to be conveyed which is being discharged into the lower end of the trough 61 from the hopper 113. The extensible trough section 107 is provided to prevent any of the matter to be conveyed from draining back to the trough 61 and being lost through its open, lower end. The trough section 107 is made extensible so that it can be extended to accommodate itself to the various positions of the sprocket wheels 73.

As best seen in Figures 4 and 5, the blades or conveyer elements 98 fit snugly within the rounded bottom of the trough 61 and extend from side to side thereof but terminate substantially below the level of the rim of the trough 61 so that the spaces in the trough 61 between the blades 98 cannot be overloaded to an extent that the material being conveyed will overflow the rim of the trough 61 and possibly reach the chains 74. Should any of these aforescribed spaces in the trough 61 be overloaded, the material would merely flow over the blades 98 without escaping from the trough 61 and to the next space therebehind. Obviously, if concrete, mortar, plaster or similar material, not shown, is being conveyed, after the material has been carried by the blades 98 to the upper end of the trough 61 and is discharged therefrom into the outlet conduit 63 and the blades 98 have passed around the idler sprocket wheels 73, some of the conveyed material will have adhered to the blades 98 and will drip therefrom as the blades 98 move back toward the lower end of the frame structure 17. Most of this material, as illustrated in Figures 4 and 5, will drop directly back into the trough 61 while some of the material will drip onto the shields 101 and flow therefrom into the trough 61. The remainder will drip either onto the shields 103 or the plates 109 and drip from either point onto the shields 101 and eventually return to the trough 61 so that none of the material can possibly come into contact with the chains 74. This is obviously a very important and critical feature of the applicant's invention since should material such as cement, plaster or mortar come into contact with the chains 74 this material would obviously dry while the machine 15 was not in operation and thereafter prevent the chains 74 from flexing and consequently prevent operation of the machine and this is true regardless of the type of endless flexible conveyer that might be substituted for the chains 74.

In most conveyers for conveying cement, mortar or plaster, the material is carried by endless conveyer means. In the applicant's invention, on the other hand, the material is pushed and/or pulled by the blades 98 in the trough 61 and consequently the material is constantly agitated while in transit so that the material will be mixed as thoroughly or more thoroughly when it is discharged into the outlet 63 as when it was discharged into the trough 61.

The truck 16 is provided with the extensible side rails 18 so that it can be extended for properly balancing the weight of the upper, free end of the frame structure 17 regardless of its angle of inclination. In towing the machine 15 to different jobs where it is to be employed the frame structure 17 is preferably disposed in a horizontal position and the flooring 30 is therefore provided with the upstanding abutments 115 on which a portion of the frame structure 17 can rest for balancing it on the truck 16.

Figures 12, 13 and 14 illustrate a slightly modified form of the machine, designated generally 15' and which is like the machine 15 in every respect except that it is only adaptable to the larger sized machines which are not provided with the drag members and instead of the plates 69, the machine 15' is provided with plates 69' having two pairs of bearing bracket 71' for journaling two shafts 72' on each of which is keyed two small idler sprocket wheels 73' over which are trained the chains 74 and which are adjustable by the bolts 68 and nuts 70 for tensioning the chains 74. The construction of the machine 15' is obviously not adaptable for a conveyer provided with the drag members 106 because the blades 98 which are adjacently disposed at times assume positions substantially at right angles to one another and would therefore be required to bend excessively. The operation of the machine 15' is identical with that of the machine 15, previously described, and a further description thereof is therefore deemed unnecessary.

Various modifications and changes are contemplated and may obviously be resorted to as only a preferred embodiment of the invention has been disclosed.

I claim as my invention:

A conveyer comprising a support, an elongated upwardly opening trough disposed therein, an upper and a lower pair of inwardly opening channel members mounted in the support and above the trough, driven endless conveyer chains mounted to move through the channel members, said chains and channel members being spaced laterally away from the trough, transverse bars connecting corresponding portions of the chains, supporting members secured to and projecting outwardly from the bars, conveyer elements attached to said supporting members and constructed and arranged to move longitudinally through the trough for conveying material disposed therein, said supporting members being formed of rigid material and being rigidly connected to the bars, said conveyer elements being formed of yieldable material, and flexible drag members connecting each of the conveyer elements to the supporting member of the next preceding conveyer element.

WILLIAM H. REIMANN.
